UNITED STATES PATENT OFFICE.

CHARLES A. GILDEMEYER, OF HADDONFIELD, NEW JERSEY.

DESIGN FOR AN INK-WELL.

SPECIFICATION forming part of Design No. 22,311, dated March 28, 1893.

Application filed February 20, 1893. Serial No. 463,122. Term of patent 14 years.

To all whom it may concern:

Be it known that I, CHARLES A. GILDEMEYER, a citizen of the United States, and a resident of Haddonfield, Camden county, New Jersey, have invented a new and original Design for an Ink-Well, of which the following is a specification.

My design for an ink well is fully illustrated in the accompanying drawings, in ^{to} which—

Figure 1, is a perspective view illustrating my design; and Fig. 2, is a side view.

The body portion A of the ink well is quadrangular in shape having vertical ribs a, and ¹⁵ projecting above this body is a quadrangular name plate section B, the top of which is inclined toward the front of the ink well, and is depressed at b', forming a rib or frame b.

Projecting from the front of the body portion is a dipping pit portion D narrower than the body portion, and having a rib d at its base which merges into the body portion. On the upper portion of the dipping pit section is a flange d' arranged at an incline toward the front of the well. ²⁵

I claim—

The design for an ink well as herein described and shown.

In testimony whereof I have signed my name to this specification in the presence of ³⁰ two subscribing witnesses.

CHARLES A. GILDEMEYER.
